UNITED STATES PATENT OFFICE.

MARY MORRIS, OF NEW LONDON, CONNECTICUT.

SAVINGS BANK.

Application filed January 11, 1927. Serial No. 160,381.

This invention relates to a savings bank having various features of novelty and advantage.

An aim of the invention is to provide an improved, simple, effective and safe savings bank by means of which the spirit of systematic saving is fostered.

A further aim of the invention is to provide an improved savings bank which is normally concealed or camouflaged so that it will be overlooked by one inclined to surreptitiously tamper with the same.

A still further aim of the invention is to provide a bank of this sort which can be opened only by an authorized custodian or agent.

Another aim of the invention is to provide an improved savings bank wherein, if an unauthorized person should open the locked or outside door of the bank, he could not gain access to the money within the bank without knowing how to open an inside door, thus making the bank more or less proof against theft.

Another aim of the invention is to provide an improved bank of this sort with a main door which can be unlocked only by one authorized to do so, and with an auxiliary door which can be opened only by one knowing the secret as how to do it, this auxiliary door being so arranged that, when it is in open position, it will prevent the coins within the bank from falling out of the same.

Other objects will be in part obvious and in part pointed out more in detail hereinafter.

The invention accordingly consists in the features of construction, combination of elements and arrangement of parts which will be exemplified in the construction herein-after set forth, and the scope of the application of which will be indicated in the appended claims.

As an instance of a use to which my improved bank may be applied, reference may be had to the systematic saving of small amounts to be applied to the payment of regularly due amounts, such, for instance, as the payment of insurance premiums. With a bank constructed in accordance with the present invention, the insured, particularly one of tender age, may, at regular times, for instance each day or each week,

drop into the bank the necessary amounts which will be sufficient to meet say monthly premiums. The key, by which the bank may be opened, or the combination, in the event the bank is provided with a combination lock, may be retained by the insurance agent so that the insured or any unauthorized person cannot gain access to the amounts deposited in the bank. The insured, of course, would know where the bank is situated but, having no key, he could not gain access thereto. As previously stated, the bank is concealed, or at least partially hidden, from view so that any one not familiar with the position of the bank, and who might be inclined to tamper with the same, could not readily discover it. In the event that the bank should be discovered by some unauthorized person, he could not gain access to the bank although he may remove the concealing or face plate. Should such an unauthorized person have the opportunity and ingenuity to pick the lock on the outside door, he would still have the inside door to open, and he could not open this door unless he knew the secret for doing so.

In the accompanying drawings, wherein I have shown one of the many embodiments which the present invention may take:

Figure 1 is a front view with the concealing plate or grid in place;

Fig. 2 is a view similar to Fig. 1 with the face plate removed;

Fig. 3 is a horizontal sectional view taken substantially on line 3—3 of Fig. 1;

Fig. 4 is a vertical central view taken substantially on line 4—4 of Fig. 1;

Fig. 5 is a view similar to Fig. 4, but showing the doors in open positions; and

Fig. 6 is a detail view showing the manner in which the outer door, when moved to full position, releases the lock for the inner door.

Referring to the drawings in detail, 10 designates a support of any suitable kind or sort. This support may be provided by the walls of a building, or may be a piece of furniture, such as a desk. The support 10 is provided with a recess in which is positioned my improved bank having a body portion or receptacle 11 placed in upright 105 position. The front wall 12 of the recep-

tacle has a flange 13 which defines the opening through which access may be had to the interior of the bank. This opening is normally closed by an outside or main door 14 and an auxiliary or inside door 15. The main door is hinged for swinging movement in a horizontal plane, the hinges being designated by the numeral 17. As illustrated, the main door, when closed, is adapted to engage against the outside edge of the flange 13. This main door carries a lock of any suitable construction, the lock being designated by the numeral 18 and being shown as having a key-hole 19. Obviously, instead of a key operated lock, a combination lock may be provided. The lock has a bolt 20 adapted to engage in an opening 21 in the flange. The main door has, preferably adjacent its upper edge, a horizontal coin receiving slot 22.

The auxiliary door, which is designated by the numeral 15, is located, when in closed position, within the flange 13 and is pivoted adjacent its lower edge as at 26 so that when opening the auxiliary door it will swing down to horizontal position, as shown in Fig. 5. When the door 15 is released, a spring 27 may be employed for throwing it into open position. By preference, the auxiliary door has side flanges 28 and a flange 29 at its upper end so that, when the door is thrown open, in the event the coin should fall or roll onto the door 15, these coins cannot fall off of the edges thereof. In order to secure the auxiliary door in closed position and to prevent any one from opening this door, unless he knows how to do so, I provide secret locking means which, in the present instance, is in the form of a spring 30 connected to one of the flanges 28, as at 31. The free end of this spring has a head 32 which is adapted, when the auxiliary door is locked, to engage in the registering openings 33 and 34 positioned in the flanges 28 and 13, respectively. The main door has, at its pivoted edge, an in-turned lug 35 which, when the main door is thrown to the full open position shown in Fig. 6, is adapted to engage the head of the spring 30 and thereby force this head out of the opening 34 thereby releasing the auxiliary door and permitting the spring 27 to throw this door into the open position shown in Fig. 5. The auxiliary door has a coin receiving slot 37 adapted to register with the slot 22 in the main door when both of these doors are closed.

For the purpose of concealing the bank, I provide a face plate 40 which may be removably secured in place by screws 41. Preferably, this face plate is similar to the face plate of an electric switch so that any one looking at this structure would not perceive that it concealed a bank. The face plate also has a slot or coin receiving open-

ing 42 adapted to register, as shown in Fig. 4, with the coin receiving slots of the two doors.

It will be understood from the foregoing description, taken in connection with the accompanying drawings, that only an authorized person, such as an insurance agent who collects the premiums and who is familiar with the location of the bank and the manner in which it may be opened, can gain access to the savings within the bank. This agent may remove the face plate, and, by making use of the key or the combination which he has in his possession, can open the outside door. By throwing the outside door to the full open position shown in Fig. 6, the lock for the inside door is released, whereupon the inside door will be thrown down to the open position shown in Fig. 5 so that access can be had to the coins within the receptacle. After the agent has collected the money, he can very easily close and lock the doors and apply the face plate. If an unauthorized person should, by using unusual ingenuity, find the bank and open the outside door, he would be baffled as to how to open the inside door. Should such an unauthorized person be able to open the outside door, the spring lock 30 would offer sufficient resistance to the outside door being thrown to full open position that the unauthorized person would not think of forcing the door to that full open position and, unless he knew enough to so open the door, he could not gain access to the interior of the bank because the auxiliary door remains locked.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A savings bank of the character described including a support having a recess, a bank within said recess and having a door provided with a lock and a coin receiving slot, and a removable face plate concealing said bank and having a coin receiving slot registering with said first mentioned slot.

2. A savings bank of the character described including a support having a recess, a bank located in said recess and having a main door and an auxiliary door, a lock for

each of said doors, registering coin receiving slots in said doors, and a removable plate in front of said bank having a coin receiving slot in registry with said mentioned slots

5 when the doors are closed.

3. A savings bank of the character described including a support having a recess, a bank within the recess and having an outer door pivoted for swinging movement in a 10 horizontal plane, a lock on said outer door, an inner door pivoted for movement from a vertical to a horizontal position, a lock for said inner door, and registering coin receiving slots in said doors.

15 4. A savings bank comprising a receptacle having an opening in one wall thereof, a main door pivoted for swinging movement in a horizontal plane and having a coin receiving slot and a lock, an auxiliary door pivoted for movement from an upright to a 20 horizontal position and having a flange at each side edge and at its upper edge, said

auxiliary door having a coin receiving slot adapted to register with the slot of said main door, and a lock for said auxiliary 25 door.

5. A savings bank of the character described including a support having a recess, a receptacle within the recess and having an opening in one wall thereof, a main door pivoted for swinging movement in a horizontal plane and having a coin receiving slot and a lock, an auxiliary door pivoted for movement from an upright to a 30 horizontal position and having a flange at each side edge and at its upper edge, said auxiliary door having a coin receiving slot adapted to register with the slot of said main door, a lock for said auxiliary door, and a face plate concealing said bank, said 35 face plate having a slot adapted to register with the slots in said doors.

MARY MORRIS.
